HORACE DRUMMOND BLACK, OF LONDON, ENGLAND.

PAPER CUTTING AND COLLECTING MACHINE.

1,027,099.

Specification of Letters Patent.

Patented May 21, 1912.

Application filed April 28, 1911. Serial No. 623,886.

To all whom it may concern:

Be it known that I, HORACE DRUMMOND BLACK, a subject of the King of Great Britain, residing at 56 Tabernacle street, 5 Finsbury, London, England, have invented a new and useful Paper Cutting and Collecting Machine, of which the following is a specification.

This invention relates to a machine for cutting or dividing into separate books or pads counter check and like books which are made with two or more forms on a leaf so as to form a strip of books, and for collecting in numerical order the books after the cutting operation.

It is found in practice that books of the above type cannot be cut on ordinary paper cutting machines or guillotines without being damaged, by reason of the fact that the 20 stub or edge of the book, where the leaves are bound together, being of less thickness than the body of the same, where the leaves are folded on each other, cannot be clamped by the platen of the cutting machine and is 25 consequently liable to be torn while being cut, particularly as each leaf is perforated where the difference in thickness occurs.

The object of my invention is to construct a machine the cutting operation of which 30 will not possess the above defect and at the same time the books will be cut more expeditiously and their numerical sequence be maintained during their delivery from the machine.

According to the invention I provide in a 35 machine a series of pairs of fixed and movable knives pivoted together at one end, a series of platens or the like for clamping each book strip while being cut, means for 40 feeding the book strips to the knives and means for collecting them after being cut in the same order as that in which they are fed to the knives.

In a suitable arrangement for carrying 45 out the invention I provide a table mounted on suitable side frames and having a moving fence thereon, either in the form of an endless band with projections thereon, or designed to be reciprocated to carry the book 50 strips between the series of fixed and pivoted knives. The knives are mounted above an opening in the table and are adjustable across the machine so that they can be spaced according to the lengths the strips 55 have to be divided into. The fixed or lower

knives are arranged horizontally and their upper surfaces are flush with the table and form a support for the strips when between the knives. The front ends of the upper knives are jointed to a horizontal bar reciprocated vertically in two upper side frames so that the said knives have imparted to them a scissors-like action.

A clamping platen is provided in conjunction with each pair of knives to clamp the 60 work during the cutting operation, these platens being attached to a second horizontal bar also reciprocated vertically in the upper part of the side frames.

The book strips are carried between the 70 knives by the moving fence with the stub edge forward to receive the cutting action of the knives first, and when the cut has been completed and the pivoted knives and platens returned to the open position, the 75 severed books are guided on to a traveling endless band or the like which carries them toward the back of the machine, where the books are allowed to fall in an upright position on to a horizontal collecting platform 80 where they are moved and maintained in proper sequence by a horizontally reciprocating fence and a vertically reciprocating prong fence coöperating in a known manner.

To enable the invention to be fully understood I will describe the same by reference to the accompanying drawings, in which:—

Figure 1 is a side elevation of a machine constructed according to my invention. Fig. 2 is a front elevation of the same, and 90 Fig. 3 is a plan thereof. Fig. 4 is a sectional side elevation of the machine. Fig. 5 is a side elevation of a portion of the feeding mechanism drawn to an enlarged scale, and Fig. 6 is a plan thereof.

a, a are the side frames of the machine and *b* is the table connecting the said frames together and on which the work is initially placed as hereinafter described.

c, d indicate each pair of fixed and movable knives. In the drawings two pairs of knives are shown for cutting a book strip into three books. Each fixed or lower knife *c* is carried by a bracket *c*¹ adjustably attached to a recessed portion *b*¹ of the table 100 *b* and the movable or upper knife *d* is carried on a bar *d*¹ pivoted at one end at *d*² to the bracket *c*¹, the other end of the bar *d*¹ being jointed to an adjustable collar *e*¹ on a bar *e* extending across the machine and 110

designed to be reciprocated in guides e^1 in the upper part of the side frames a , a by means of connecting rods e^2 , actuated by cranks e^3 on a shaft f , the said shaft being 5 rotated from the main shaft g through the medium of gear wheels h , h^1 , shaft h^0 and gear wheels h^2 , h^3 .

g^1 , g^2 are fast and loose pulleys on the shaft g .

10 i , i are a pair of endless sprocket chains passing around sprocket wheels i^1 , i^2 below the level of the top of the table b but working in parallel slots b^1 , b^1 therein, the sprocket wheels i^1 , i^2 being carried on a 15 shaft i^3 designed to be driven from the gear wheel h^3 through the medium of the gear wheel i^4 , shaft i^5 , sprocket wheel i^6 , sprocket chain i^6 and sprocket wheel i^7 . The sprocket wheels i^2 , i^2 revolve on fixed studs i^8 , i^8 carried by the table b .

20 j , j are the projections carried by the chains i , i and constituting the fence for feeding the book strips between the knives c , d one of said strips with the stub end 25 forward being indicated in position in front of the fence by the dotted lines A in Fig. 4. The position of the book strip between the knives c , d for each cutting operation is determined by stops k , k , and as the strip 30 when in this position would form an obstruction to the continued movement of the projections j , j I provide for turning the said projections back out of the way to enable them to pass the said strip. For this 35 purpose, as shown clearly in Figs. 5 and 6, which illustrate one of the said fence projections j and its supporting chain, I arrange the said projection on a pivot j^1 , and I provide it with a boss j^2 having a series 40 of notches j^3 in its periphery with either of which engages a spring pin j^4 so that the said fence will be held by the said pin either in the upright position shown in Fig. 5, or the turned down position shown by the 45 dotted lines also in the said figure. For effecting this turning movement the projection j is provided on one side with a lug k^0 designed to impinge against a stud k^1 carried by a bracket k^2 adjacent to the sprocket 50 wheel i^2 , with the result that the projection j is turned from the upright position shown in the full lines into the turned down position shown by the dotted lines. By this construction it will therefore be seen that 55 after having moved the strip to the position shown at A¹, Fig. 4, the projection j will be freed from the said strip. In order that each projection j shall be again raised to the upright position in order to again act as a 60 fence for another book strip, a plate l is provided having a cam surface l^1 with which a roller l^2 carried on an arm l^3 on the projection j will impinge as the said projection 65 is again rising toward the surface of the

b^2 is a cross fence and b^3 a side fence, both being attached to the table b and serving to determine the initial position of the strip to be severed on the table b . As the fence b^3 is in the line of movement of the lug k^0 70 on one of the fence projections j and would obstruct the latter, it is pivoted at one end to the table b , the lug k lifting it slightly in passing.

75 m , m are the platens for clamping the book strips when in the position A¹, the said platens being arranged to clamp the strips against the lower knives c , c and being carried by vertical rods m^1 , m^1 , adjustably supported by a bar m^2 extending across the machine and working in guides m^3 in the side frames thereof, the said bar being reciprocated vertically by rods m^4 , m^4 having rollers engaging cam grooves m^5 , m^5 in disks m^6 , m^6 mounted on a shaft n operated 85 from the shaft f through the medium of gear wheels n^1 , n^2 .

80 In order to accommodate the platens to varying thicknesses of book strips, springs o , o are arranged between the said platens and the underside of the cross bar m^2 .

85 p is the traveling endless band on to which the books or portions of the severed strip are deposited after the cutting operation, the said band passing around rollers p^1 , p^2 , the roller p^1 being rotated from the gear wheel n^2 through the medium of the gear wheel q , shaft r , bevel-wheels s , s^1 , shaft s^2 , and bevel wheels s^3 , s^4 , the bevel wheel s^4 being mounted on the shaft s^6 100 carrying the roller p^1 .

90 Instead of allowing the portions of the severed strip to fall from between the knives directly on to the band p , I prefer to employ means for positively transferring them to the said band. These means advantageously comprise a series of pairs of supporting plates t , and covering plates t^1 , the supporting plates t being normally flush 95 with the top of the table, as indicated by the dotted lines in Fig. 4, with the covering plates above them sufficient space being left between the said plates for the book strip to pass into the position A¹, so that 105 after the cutting operation the two series of plates are moved down from the dotted line position to that shown by the full lines, the severed strips supported on the plates t then sliding from the latter on to the band p .

110 The requisite oscillatory movement is 115 imparted to the plates t by a rocking shaft u , carrying the said plates, from a cam u^1 on the edge of the disk of one crank c^3 , rod u^2 and crank arm u^3 on the shaft u . The plates t^1 are hinged to the lower ends of upright rods v , v , passing through holes in the cross bar m^2 and adjustably carried on a cross bar v^1 designed to be reciprocated on upright guide rods v^2 on the side frames a , a of the machine, the reciprocation being 120 125 130

effected from another cam w on the edge of the disk of the said crank e^3 through the medium of the rod w^1 , lever w^2 , carried upon one end of the shaft w^3 , mounted in 5 bearings in the frame sides a and levers w^4 on each end of the said shaft w^3 and links w^5 , the lever w^2 being formed integral with one of the levers w^4 . The plates t^1 are normally held in an inclined position so as to 10 conform more or less to the inclination of the plates t when the latter are moving down carrying the severed portions of the book strip. As, however, it is necessary that the plates t^1 should assume a horizontal position when raised in position to receive the book strip to be severed, depending stops x, x are provided, against the lower ends of which the plates t^1 impinge and are turned to the horizontal position. 15

y is the horizontal collecting platform for receiving the severed portions of the book strips from the band p and collecting them in proper sequence this being effected 20 by the horizontally reciprocating fence y^1 supported upon guide rods y^2 and actuated from cam grooves y^3 in disks y^4 through the medium of the rollers y^5 links y^6 double armed levers y^7 and links y^8 .

z is the vertical reciprocating prong-fence coöperating with the fence y^1 , the severed portions of the book strip falling into the space between the two fences in an upright position and being pressed by the fence y^1 25 toward the fence z , the latter being at the same time lowered out of the way of the said deposited strip and being again moved up into recesses z^1, z^1 , in the fence y^1 so that when the latter moves again forward to 30 form a space for the reception of further severed strips the fence z will hold the severed portions of the strip previously referred to against the movable stop fence z^2 . The pronged fence z is supported at each 35 end on a slide z^3 which slides are reciprocated in upright guides z^4, z^4 by levers z^5 actuated by cam grooves z^6 in disks z^7 .

The operation of the machine is as follows:—A strip to be severed is placed in 40 position on the table b with its back edge resting against the fixed fence b^2 and with one of its ends bearing against the movable side fence b^3 and assuming the projections j forming the feeding fence have not risen 45 to project above the table, on starting the machine the said projections will come into position above the table top and into contact with the back edge of the book strip which will be moved into position between 50 the knives against the stops k, k . The platens m and knives d, d will then simultaneously descend to secure the strip and sever it into the required book lengths which will then be partly supported upon 55 the lower knives c, c and plates t, t the said

latter plates t, t together with plates t^1, t^1 then descending and depositing the severed portions of the strip upon the band p which will transfer them into the space between the fences y^1 and z . Each severed strip is 60 then in turn moved along the collecting platform y and packed one behind another in their proper sequence between the fence z and the movable stop fence z^2 . When a sufficient number of strip portions or books 65 have been collected on the platform y the stop fence z^2 may be removed to allow of the removal of the said books the fence z^2 being returned into position against or in proximity to the pronged fence z . 70

Although I have described the machine as designed to sever the book strips into three portions, by altering the number of knives, platens and transferring plates and adjusting them to the required distances 75 apart, the strips may be severed into a greater or less number of portions. 80

Claims.

1. In a machine of the class described, the combination with a plurality of cutting devices, each device consisting of a fixed cutting blade and a movable cutting blade, of a pressure platen for each cutting device for clamping the work, said pivoted cutting blade and said pressure platen being movable and independently operated. 90

2. In a machine of the class described, the combination with a plurality of cutting devices, each consisting of a fixed cutting blade and a movable cutting blade, of a pressure platen for each cutting device, 100 means for moving the said cutting blade and means separate therefrom to cause the said pressure platen to force the work down and hold it upon the fixed cutting blade. 105

3. In a machine of the class described, the combination with a plurality of cutting devices, of an endless feeding device, said feeding device being provided with projections to engage and move the work and 110 means for moving said projections backwardly away from the work when the latter is in cutting position and to move said projections forwardly and upwardly to engage the said work to begin feeding. 115

4. In a machine of the class described, the combination with a plurality of cutting devices, of feeding devices therefor, of supporting plates and depressing platens above the same, an endless carrier for carrying the 120 materials after being cut, and means for causing the supporting plates and depressing platens to deliver the cut material to said endless carrier.

5. In a machine of the class described, the combination with a plurality of cutting devices, of a feeding mechanism, a clamping mechanism, supporting plates and depressed platens, a collecting platform, an endless carrier adapted to deliver to said collecting 125 130

platform and means for causing said supporting plates and depressing platens to deliver the cut materials to said endless carrier.

6. In a machine of the class described, the combination with a fixed or stationary cutting blade, of a supporting plate normally flush with the stationary blade, a vertically movable depressing plate, an endless carrier to carry away the materials after they are cut and means for moving the depressing plate to cause the same and the supporting plate to deliver the cut materials to the said carrier.

7. In a machine of the class described, the combination with a cutting mechanism con-

sisting of a fixed and a pivoted cutting blade, of a supporting plate normally parallel and flush with the fixed cutting blade, a vertically movable depressing platen above said supporting plate and normally at an angle to the fixed cutting blade, means for moving said depressing platen vertically and means for turning the depressing blade upon its pivot to a position parallel to the fixed cutting blade.
